US00D762256S

(12) United States Design Patent
Han et al.

(10) Patent No.: US D762,256 S
(45) Date of Patent:  Jul. 26, 2016

(54) PROJECTOR

(71) Applicant: LG ELECTRONICS INC., Seoul (KR)

(72) Inventors: Youngsoo Han, Seoul (KR);
Yoonkyeong Lee, Seoul (KR);
Byungmu Huh, Seoul (KR);
Myungwhoon Lee, Seoul (KR); Angus Dick, Seoul (KR)

(73) Assignee: LG Electronics Inc., Seoul (KR)

() Term: 15 Years

(21) Appl. No.: 29/530,838

(22) Filed: Jun. 19, 2015

(30) Foreign Application Priority Data

Dec. 19, 2014 (KR) 30-2014-0062169
(51) LOC (10) Cl. 16-02
(52) U.S. Cl.
USPC D16/230; D16/225

(57) CLAIM

The ornamental design for a projector, as shown and described.

DESCRIPTION

FIG. 1 is a front, left side, perspective view of a projector showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown in the figures represent portions of the projector and form no part of the claimed design.

1 Claim, 5 Drawing Sheets
